UNITED STATES PATENT OFFICE.

FRANK W. MORSE AND FRANK B. HUBBARD, OF WARREN, OHIO.

HOT-AIR ENGINE.

No. 822,463.

Specification of Letters Patent.

Patented June 5, 1906.

Application filed September 9, 1904. Serial No. 223,840.

To all whom it may concern:

Be it known that we, FRANK W. MORSE and FRANK B. HUBBARD, citizens of the United States, residing at Warren, in the county of Trumbull and State of Ohio, have invented certain new and useful Improvements in Hot-Air Engines; and we do declare that the following is a full, clear, and exact description of the invention, which will enable others skilled in the art to which it appertains to make and use the same.

Our invention relates to improvements in hot-air engines; and the invention consists in the novel arrangement of parts substantially as hereinafter shown and described, and more particularly pointed out in the claims.

Our object is embodied in a hot-air engine adapted to give increased power over other known forms of hot-air engines, especially in the small types.

Accessibility to the interior of the working cylinders and convenience in making repairs is an object also embodied in the construction.

We aim to produce an engine adapted to have a constant and fresh air supply, and thereby maintain an even running of the engine continuously without loss of power.

In the accompanying drawings, Figure 1 is a side elevation of our improved engine, and Fig. 2 is a central sectional elevation of the engine at right angles to Fig. 1. Fig. 3 is an enlarged sectional detail of the controlling-valve located in the main port between the air-cooling cylinder and hot-air cylinder. Fig. 4 is a sectional view, enlarged, of the air-pressure relief-valve for the hot-air cylinder.

The engine comprises a main casting A, made in one piece with a working cylinder B and a hot-air cylinder portion A' at opposite ends and with a connecting duct or passage a² leading from the upper end of working cylinder B down and into the lower end of portion A' of hot-air cylinder C. Removable extensions C' and C², bolted upon the upper and lower faces, respectively, of casting A, complete cylinder C, and a water casing or jacket C³ is also mounted upon and incloses upper extension C'. A plug-valve a³ is mounted in passage a² to regulate the speed and power of the engine and is provided with an air-intake passage a⁴ and a check-valve a⁵ to prevent escape of air from port a². A suitable pump connection is made with the screw end a⁶ of said valve, and air is forced into the cylinders before starting the engine.

Thereafter check-valve a⁵ remains closed from the pressure within.

Working cylinder B is provided with a piston D, connected by rod d with crank 2 on shaft 3, which carries balance-wheel 4 and which shaft is mounted in bearings supported by base L. Hot-air cylinder C is provided with a very light weight hollow plunger E, which is filled with asbestos e or like material and is of less diameter than the interior of said cylinder. Plunger E has an upper vertical stem e', adapted to slide in bearings e² and f to keep the plunger in perfect running alinement and out of contact with the cylinder. Bearing f is part of standard F, adjustably mounted upon a water-jacket C³ by bolt f', and this jacket is removably secured to the flanges of extension C'. A yoke H pivotally connects stem e' with crank 5 on shaft 3, and said crank is set at substantially eighty-five or ninety degrees in advance of crank 2. A heater of any suitable construction, such as a gasolene-burner I, is located immediately beneath the lower end of cylinder C, and a heat, confining jacket or casing J depends from the flange of cylinder extensions C² and is spaced apart from said cylinder and provided with openings j at its top for the escape of the heat from burner I.

The engine as thus constructed is designed, primarily, for operating a water-pump K, mounted upon base L of the engine, and said pump is connected by a yoke connection M with piston D. Pump K is located in the line of water-supply N and forces the water through pipe N' into the water-jacket b of working cylinder B, and thence through pipe-coupling b' into water-jacket C³ of extensions C', and thence through outlet-pipe b² to its ultimate destination.

For greater efficiency and power we have also provided an auxiliary air-pump O, having a flap-valve piston O', said pump being mounted upon head 8 of working cylinder B and having its piston O' connected with piston D by short shaft o². An air-pipe P connects pump O with the lower portion of cylinder extension C' and conducts the cool air which is taken from the outer atmosphere past the piston O' into the lower end of cylinder extension C², and a check-valve P' prevents the return of the air to the pump. To guard against an overpressure of air within cylinder C, we provide a spring-controlled relief-valve p³, located at the upper end of cylinder C, and said valve automatically opens to

relieve the pressure in the upper end of the cylinder when the pressure exceeds a predetermined amount and is controlled by set-screws p^4 on said valve.

5 Main casting A is supported above base L by four tubular uprights L', one at each corner, and a hand-lever L² is pivoted upon a bracket L³, secured to one of said uprights, and a link or other suitable connection L⁴ is 10 detachably connected to yoke M of pump K to operate the pump by hand power through lever L² when the engine is not running. A faucet N² is attached to pipe N' for the withdrawal of water, and a check-valve N³, placed in said pipe, prevents a backflow of 15 water from water-jackets b and C³.

To start the engine, air is first forced into passage a² and the cylinders by means of a separate air-pump, which is attached to valve 20 a³. Burner I is then started and lower extension C² of cylinder C heated to a high degree. Thereupon the engine starts running upon an initial movement given to fly-wheel 4 and continues to run until valve a³ is closed or 25 constant open connection is established with the outer atmosphere. As piston D rises the cool air in cylinder B is forced through duct or passage a² into cylinder C beneath plunger E. As plunger E rises the heated air passes 30 into working cylinder B and acts upon the piston therein. The upper portion of cylinder C is water-jacketed to cool the air at that end, and when the plunger rises the cool air is displaced and forced down to the lower end 35 of said cylinder. Balance-wheel 4 acts to carry the plunger over the dead points. A fresh supply of air is taken in from the outside from time to time, and any surplus is also automatically disposed of. The first-named 40 result is obtained by air-pump O, which forces a supply of air from connection P into

cylinder C, and relief-valve p³ is utilized to the latter end.

What we claim is—

1. In a hot-air engine, the combination of 45 a working cylinder with an air-heating cylinder, an open passage connecting said cylinders, a plunger in said air-heating cylinder and a piston in said working cylinder and crank connections for the same, a heater for 50 said air-heating cylinder and an auxiliary air-pump connected with said piston, air connections between said pump and air-heating cylinder, a check-valve in said connections, and an air-pressure relief-valve for said air-heating cylinder.

2. In a hot-air engine, a casting with a working cylinder and a portion of an air-heating cylinder embodied therein, separate upper and lower extensions to complete said 60 air-heating cylinder, a water-jacket for the upper extension and a heater-casing for the lower extension, a heater beneath said air-heating cylinder, a piston for said working cylinder and a plunger for said air-heating 65 cylinder, a crank-shaft and balance-wheel thereon and crank connections between said crank-shaft and said piston and said plunger, an auxiliary air-pump for said engine and air connections between said auxiliary air-pump and the lower end of said air-heating cylinder, and means to control the flow of air to said heating-cylinder from said auxiliary pump, and an automatic air-relief valve for 70 the upper end of said air-heating cylinder. 75

In testimony whereof we sign this specification in the presence of two witnesses.
